COTTON PICKER NEEDLE

James E. Hutchins, Jr., and George T. Comeaux,
Greenville, Miss.

Application June 22, 1951, Serial No. 232,968

3 Claims. (Cl. 56—50)

1.

This invention appertains to improvements in the construction of picker needles, employed in cotton picking machines.

The primary object of this invention is to provide an improved needle assembly, wherein the needles are detachably secured in a dependable manner to the supporting spindles, which are rotated by a drive shaft within a spindle carrier member or drum. The needles rotate with the spindles, which are driven by the drive shaft, and are barbed to grasp the cotton fibres of matured bolls prior to winding the cotton thereonto and extracting it from the bolls. The barbs on the needles must be sharp, so that the barbs will effectively grasp and engage the fibres in gathering the crop. When the barbs become dull and worn in use, the needles must be replaced and, therefore, it is the primary object of this invention to provide means for easily and conveniently replacing the needles, without necessitating a replacement of the spindles. Also, it is the purpose of this invention to provide a replaceable needle assembly, which will not only enable needles to be repaired and replaced in a minimum of time but will also appreciably reduce the expense involved.

These and auxiliary objects and structural features of merit are attained by this invention, the preferred embodiment of which is set forth in the following description and illustrated in the accompanying drawing, wherein:

Figure 1 is a central vertical sectional view taken through a spindle carrier drum or member, which houses the driving means for the picking needles, and showing the needle units in side elevation;

Figure 2 is an enlarged partial longitudinal sectional view taken through one of the needle units and taken upon line 2—2 of Figure 1;

Figure 3 is an enlarged transverse sectional view taken on line 3—3 of Figure 2.

With continued reference to the accompanying drawing, and particularly to Figure 1, a section of a spindle carrier or drum 10 is illustrated, the same being depicted with two needle units 12 and 14, which are identically constructed and similarly attached to the carrier or drum. The carrier member or drum 10 is of a length to support a plurality of needle units, which are disposed in parallelism, the carrier member being maintained, during operation of the picking unit, in an upright or vertical position and being revolved about a closed horizontal path, whereby the needle units are projected into the cotton plant row for grasping the cotton fibres of ma-

2.

tured bolls and winding the cotton fibres thereon. The needle units are carried past a mechanism for brushing the picked cotton from the needle units and then subjected to a moistening apparatus for moistening the needles prior to the projection of the needles into another cotton plant row in initiating a succeeding cycle.

The carrier or drum 10 houses a drive shaft 16, which is axially disposed therein and which is supported by bearing units 18. The bearing units are fixedly circumscribed about the hubs 20 of the gears 22 and the hubs of the gears are fixed by transverse pins 24 to the shaft 16.

The drum or carrier member is formed with longitudinally spaced threaded openings 26, which are intersected by a vertical groove 28, the groove defining a passage for a lubricant for lubricating the bearings of the supporting spindles of the needles, as will be later described.

Each of the needle units includes a hollow spindle holder member 30, which is formed with an exteriorly threaded inner end 32 and a faceted intermediate section 34, which is provided for engagement by a wrench to facilitate screwing the end 32 into the threaded openings 26 in the carrier member or drum 10. Axially spaced bearing sleeves 36 and 38 are disposed within the holder member 30, adjacent the ends thereof, the sleeves being spaced apart at their adjoining ends to define an annular chamber 40. The chamber is provided to receive a lubricating medium.

The inner sleeve 38 is formed at its inner end with a radial flange 42, which abuts the inner end of the holder member and is formed with radial passages 44 for conducting oil from the groove 28. An axial groove 46 is formed in the inner surface of the bearing sleeve 38 and conducts oil from the passages 44 into the chamber 40, which defines an oil reservoir.

A spindle 48 is rotatably inserted within the bearing sleeves and a gear 50 is formed integrally with the inner end of the spindle, the gear having its outermost face enmeshed with the adjoining gear 22 on the drive shaft 16.

The spindle 48 provides a support and a connecting means for a needle 52, which is detachably fixed to the outer end of the spindle in end to end engagement and axially aligned therewith. The needle 52 includes a body portion 54, which is formed with a major end 56 and a minor end 58, barbs 60 being formed in axially spaced fashion on the outer surface of the body portion and being arranged in axial rows, which are circumferentially spaced.

A dust and moisture guard 62, which is generally conically shaped, is provided and is formed with a hub 64, circumposed on the outer end of the spindle, the major end of the guard having an annular inwardly directed flange 66, which engages behind an annular flange 68 formed on the outer end of the holder 30. The dust and moisture guard member is provided to prevent dust and moisture from penetrating the bearings and the oil reservoir, the hub of the guard member closely embracing the spindle and enabling the guard member to be effective in excluding dust and moisture.

The major end 56 of the needle is formed with an axial socket 70, for securely seating the head 72 of a connecting and attaching bolt 74. The threaded shank of the bolt is threaded in an axially disposed internally threaded socket 76 formed in the outer end of the spindle, as seen in Figure 2.

In view of the clockwise and counterclockwise rotation of the drums or carrier members 10 on the pickers, the needles are designed with right and left hand threads, complementary to the threads in the sockets 76. The major end of each needle is marked at an appropriate point on its side, with the initial letter of "Right" or "Left," as at 78. The protruding portion of the spindle is likewise marked, as at 80, so that the spindles and needles are marked to enable the average operator of a picker to make an easy replacement of the worn needle in the field.

The needle can be removed from the spindle, by inserting a wrench on the inner end thereof and unscrewing the bolt from the socket 76 in the spindle, a replacement needle then being inserted on the end of the spindle, after ascertaining the threads of the socket 76, by the marking 80 on the spindle, and determining the proper threads on the connecting bolt, by the marking 78 on the needle.

It can thus be seen that the needles can be replaced on the farm, with the worn needles being easily replaced, without necessitating removal of the spindle 48 or bearing sleeves and without any possibility of dust or moisture accumulating in the holders 30.

Having thus described the invention, what is claimed is:

1. In a cotton picker needle assembly, a spindle having a gear on one end for meshing engagement with a gear on a drive shaft, said

spindle having a threaded axial socket in its opposing end, a needle, and an axially extending member on one end of said needle having threads thereon engaged in said socket, said one end of the needle and said opposing end of the spindle being in abutting engagement.

2. In a cotton picker needle assembly adapted for use with a hollow spindle holder having open inner and outer ends, a spindle adapted to be rotatably disposed in the holder and having one end projecting beyond said inner end and having its other end projecting beyond said outer end, a gear on said one end of the spindle engageable with a drive means, a dust cap rotatably circumposed on the other end of the spindle, an annular shoulder formed on the outer end of the holder, a flange on the cap rotatably engaged behind the shoulder, a needle, one end of said needle having a threaded axially extending member and said spindle having an axially disposed threaded socket in said other end thereof threadedly engaged with the threaded member on the needle.

3. In a cotton picker needle assembly for use with a hollow spindle holder having open inner and outer ends, a spindle adapted to be rotatably disposed in the holder and having one end projecting beyond said inner end and having the other end thereof projecting beyond said outer end, a gear on said one end of the spindle engageable with a drive means, a dust cap rotatably circumposed on said other end of the spindle, an annular shoulder formed on the outer end of the holder, a flange on the cap rotatably engaged behind the shoulder, and a needle, one end of said needle having a threaded member integral therewith and extending axially therefrom, and said spindle having an axially disposed threaded socket in said other end threadedly receiving said threaded member, said other end of the spindle and said one end of the needle being in abutting engagement.

JAMES E. HUTCHINS, JR.
GEORGE T. COMEAUX.
